UNITED STATES PATENT OFFICE.

CESARE BARBIERI, OF CHICAGO, ILLINOIS.

ELEVATING-MACHINE.

1,286,202.

Specification of Letters Patent. Patented Dec. 3, 1918.

Application filed July 27, 1914. Serial No. 853,446.

To all whom it may concern:

Be it known that I, CESARE BARBIERI, a subject of the King of Italy, residing at Chicago, in the county of Cook and State 5 of Illinois, have invented certain new and useful Improvements in Elevating-Machines, of which the following is a description.

My invention relates to means for receiving 10 granular material at one level and automatically raising the same and discharging it at a considerably higher level.

The object of my invention is to provide a simple, convenient and reliable device of 15 the kind described whereby material is taken from the receiving bin or level and discharged into the elevating mechanism proper by an auxiliary device or loader arranged to operate automatically and partially counter-balance the weight of the 20 moving parts of the main elevating mechanism.

To this end my invention consists in the novel construction, arrangement and combination of parts herein shown and described and more particularly pointed out in the claims.

In the accompanying drawings wherein like or similar reference characters indicate 25 like or corresponding parts:

Figure 1 is a side elevation of an elevator equipped with my device, with parts removed to more clearly show the construction.

Fig. 2 is an enlarged detail side elevation of the auxiliary mechanism shown in Fig. 1 and associated parts.

Figs. 3, 4 and 5 are enlarged detail views 30 of the mechanism for controlling the escape of the material from the receiving bin.

In the drawings for the purpose of illustration I have shown my improved mechanism as applied to a coal handling station, in which 1 is the receiving bin, 2 the storage bin, and 3 the receptacle for elevating the material to the storage bin adapted to move in substantially a vertical path controlled by the guides 4 and operated by suitable cable or other convenient means 5 attached to the receptacle and passing over the head pulley 6 and thence to the winding mechanism 7. The receptacle 3 is provided with a discharge door 8 controlled by auxiliary guides 9, whereby the material in the 55 receptacle is discharged into the storage bin 2 when the receptacle is raised to the proper

elevation, all constructed and arranged in substantially the usual or any desired manner.

My improvement comprises apparatus for 60 receiving the material from the bin 1 and transferring the same to, and discharging the same into the receptacle 3. In the form shown the bin 1 is provided with a hopped bottom having a discharge opening 10 sub-

stantially at the apex of the hopper to permit the escape of material therefrom. A closure 11 is provided for the opening 10 arranged to operate in suitable guides 12 at

each side of the opening. A suitable container 14 is also provided of suitable form to fit beneath the opening 10 and receive material from the bin 1. A pair of guides 15-15 are provided one for each side of the

container for directing the movements of 75 the container 14 and suitable mechanism is provided for moving the container along the guides 15 from the receiving position at the

opening 10 to a position for discharging the contents of the container into the receptacle 80 3 when the receptacle is at the lower limit of its movement. In the preferred form shown the container 14 consists of a substantially

rectangular box having a discharge opening 16 in its lower side. A door 17 comprising 85 substantially one wall of the container is pivotally mounted at the bottom of the opening 16 and provided with suitable side plates 18 adapted to partially inclose the adjacent sides of the container when the

door 17 is closed and serving as side walls upon the door to form a trough and direct the material from the container 14 into the receptacle 3 when the door is opened as

shown in Fig. 1. 95

Any suitable means may be provided for controlling the operation of the door 17. As shown a lug 19 is provided upon each plate 18 and a latch 20 is pivotally mounted upon the side wall of the container 14

adapted to engage the lug 19 to hold the door closed. A spring 21 or other convenient means is also preferably provided for normally holding the latch 20 in engaging position. Suitable means are provided

for disengaging the latch and permitting the door to open. As shown a portion 22 of the latch 20 extends beyond the pivotal connection 29 attaching the latch to the container 14 and an adjustable stop 23 is pro-

vided upon the guides 15 adapted to engage the part 22 of the latch when the con-

95

100

105

110

tainer reaches the upper limit of its movement and disengage the latch from the lug 19, thus releasing the door 17.

A roller 28 is also provided upon each plate 18 adapted to coöperate with an auxiliary guide 29 positioned below the guides 15 to normally maintain the door in its closed position and to fully and positively close the same when the container starts 10 upon its return movement after discharging the material into the receptacle 3.

Any suitable means may be provided to move the container upon the arms 15. In the form shown a shaft 25 extends transversely of and is rotatably mounted at the lower end of the guides 15 and a similar shaft 26 is mounted parallel to the shaft 25 at the upper end of said guides. Each shaft is provided with suitable sprocket 20 wheels near its respective ends to carry a chain 27 extending between the shafts and the side walls of the container 14 are rigidly secured in any suitable manner to the respective chains 27. When thus arranged 25 it is obvious that the container 14 will be moved upon the guides 15 to correspond to the direction of movement of the shaft 26.

Suitable means are provided upon the container 14 to engage the closure 11 and 30 operate the same. In the form shown a projection 30 is provided upon each side wall of the container and a pivotally mounted catch 31 is provided upon the closure 11 for each projection adapted to engage the 35 projection to lock the closure to the container. A pawl 32 is also pivotally mounted upon the closure 11 adapted to engage a stationary block 33 upon the guides 15 or other convenient stationary portion of 40 the mechanism to hold the closure in position before, and close, the opening 10. The several parts are so proportioned and arranged that when the closure is locked in position before the opening 10, as the container 14 arrives in its position at the upper edge of the opening a part upon the projection 30 engages an arm 34 upon the pawl 32 and forces the pawl out of engagement with the block 33, at the same time the catch 50 31 engages the projection 30 and locks the closure to the container as shown in Fig. 5. The continued movement of the container toward the opening forces the closure out of position before the opening and permits 55 the material in the bin 1 to flow by gravity into the container. When the mechanism is operated to move the container from its position before the opening 10 the closure 11 moves with the container until the opening 10 is closed. When this point is reached 60 the inclined face 35 of the catch 31 engages a stationary member 36 thereby raising the catch 31 from the projection 30 and releasing the closure 11 from the container, at 65 the same time the movement of the pro-

jection 30 permits the pawl 32 to fall into engagement with the block 33 thereby positively locking the closure 11 in position before the opening 10.

Any suitable means may be provided to 70 rotate the shaft 26 to move the container 14. In the form shown the winding mechanism 7 is connected directly to the shaft 26 so that the movements of the container 14 will accurately correspond to, and partially counter-balance, the movements of the receptacle 3. The container 14 moves downward toward the opening 10 as the receptacle 3 moves upward to discharge its contents into 80 the storage bin 2, and when the receptacle moves downward the container is moved from its position before the opening 10 upward toward the receptacle 3 arriving at its discharging position when the receptacle 85 3 reaches the lower limit of its movement. At this point the stop 23 engages the portion 22 of the latch 20 disengaging the latch from the lug 19 and permitting the door 17 to fall open, and discharge the contents of 90 the container into the receptacle 3 through the trough formed by the door 17 and its side plates 18. The free end of the door, when thus positioned, rests upon the upper edge of the side wall of the container or 95 in the form shown upon a roller 40 rotatably mounted in suitable brackets 41 secured to the side of the receptacle in such a position that the roller projects slightly above the upper edge of the adjacent wall 10 of the receptacle and the free end of the door when resting upon the roller extends into the receptacle.

When the mechanism is operated to raise 10 the receptacle the free end of the door 17 is carried upward by the roller 40, the container 14 at the same time moving slowly down the inclined guides 15, the several parts being so proportioned and arranged that the roller 40 carries the free end of 11 the door 17 upward until the rollers 28 upon the plates 18 pass beyond the curved ends of the guides 29 and engage the guides to support the door and force the same completely closed so that the catch 20 engages the lug 19 and locks the door in its closed position ready to again receive material from the bin 1.

Having thus described my improvement 12 it is obvious that various immaterial modifications may be made in my device without departing from the spirit of my invention, hence I do not wish to be understood as limiting myself to the exact form or construction shown.

What I claim as new and desire to secure by Letters Patent is:

1. In a device of the kind described, a bin having a discharge opening in its bottom, a vertically movable receptacle, in com- 130

bination with a movable container arranged to move between said bin and said receptacle, and an operating means common to both the receptacle and the container for 5 moving them simultaneously toward or from each other.

2. In a device of the kind described, a bin having a discharge opening in its bottom, a vertically movable receptacle, in combination with a movable container arranged to move between said bin and said receptacle, and an operating means common to both the receptacle and the container for causing them to reach their respective limits of 10 travel simultaneously.

3. In a device of the kind described, a bin having a discharge opening in its bottom, a movable receptacle, in combination with a movable container arranged to move in a 15 direction substantially contrary to the movement of said receptacle between said bin and the receptacle, and an operating means common to both the receptacle and the container for causing them to reach their respective limits of travel simultaneously.

4. In a device of the kind described, a bin having a discharge opening in its bottom, a vertically movable receptacle in combination with a movable container arranged to 20 move between said bin and said receptacle, an operating means common to both the receptacle and the container for moving them simultaneously toward or from each other, and a means for automatically delivering 25 the contents of the container to the receptacle when they reach the limits of their movements.

5. In a device of the kind described, a vertically movable receptacle, means for 30 operating the same, and a bin having a discharge opening at its bottom, and a closure adapted to control the escape of material through said opening, in combination with a movable container, mechanism for moving 35 said container between said discharge opening and said receptacle, means for automatically

ically operating said closure to control the discharge of material into said container and movable means upon said container for directing material from the container into 50 said receptacle.

6. In a device of the kind described, a vertically movable receptacle, means for operating the same, and a bin having a discharge opening at its bottom and a closure 55 adapted to control the escape of material through said opening, in combination with a movable container, mechanism for moving said container between said discharge opening and said receptacle, means for automatically operating said closure to control the discharge of material into said container, and movable means upon said container adapted when closed to prevent the escape of material from said container and 60 when open to direct material from said container into said receptacle.

7. In a device of the kind described, a vertically movable receptacle, means for operating the same, and a bin provided with 70 an inclined wall having a discharge opening at its bottom and a closure arranged to move substantially parallel to the adjacent wall of said bin adapted to control the escape of material through said opening, in 75 combination with a movable container, mechanism for moving said container between said discharge opening and said receptacle, means for automatically operating said closure to control the discharge of material into said container and movable 80 means upon said container for directing material from the container into said receptacle.

In testimony whereof, I, have hereunto 85 signed my name in the presence of two subscribing witnesses.

CESARE BARBIERI.
